ELECTRIC SWITCH

Siegfried O. Unterschuetz, Chicago, and George P. Gaspar, Cicero, Ill.

Application April 25, 1947, Serial No. 743,880

2 Claims. (Cl. 200—64)

1

This invention pertains to new and useful improvements in electric switches, particularly those of the manually operable type known in the trade as "canopy switches."

General objects of the invention are to provide an article of the above-described class which is readily adaptable to mass production; which comprises a minimum number of easily produced operating parts, in consequence of which it is extremely compact, of low cost construction and easily assembled for use or disassembled for repair or adjustment should such be necessary.

Specific objects of the invention are to provide a switch having a non-conducting body with integral walls of such configuration as to provide self-insulation between current-carrying parts, a construction which reduces to a minimum arcing and short circuiting tendencies; which is free from open exterior contacts apt to short-circuit adjacent conducting surfaces.

How the foregoing objects and still other objects and advantages which will be apparent to those skilled in the art are achieved, is set forth in the detailed description which follows and shown on the drawings in which:

Fig. 1 is an exploded perspective of the principal parts of which a preferred form of switch is comprised;

Figs. 2 and 3 are fragmentary cross-sectional views taken substantially along the line 2—2 of Fig. 5, showing the relative positions of the internal parts in open and closed contact condition;

Fig. 4 is a fragmentary view of the entire switch shown with the cover therefor removed;

Fig. 5 is a cross-sectional view taken substantially along the line 5—5 of Fig. 4; and

Fig. 6 is a cross-sectional view taken substantially along the line 6—6 of Fig. 4;

As shown in Fig. 1, the switch in its entirety generally comprises a body or case 10; a pair of identical shaped contact members 30, 30; a helical torsion spring 40; a contact spider 50; a ratcheted rotor 60; a rotor actuating member 70; end parts spacers 80 (see also Fig. 6); a body or case cover 90; and cover retaining means comprising a screw 95 and a clip member (at the left of Fig. 1) 100.

Body or case 10 is a unitary structure preferably formed by the molding process of non-conducting thermosetting plastic material and is preferably generally annular in top or bottom plan view except for a laterally planar area tangential to the annular configuration of the upstanding exterior side wall 12. Planar area 11

2

has an opening 13 therein which openly communicates with an arcuate slot or chamber 14 formed within case 10 for the reception and guidance of the hereinafter described switch-actuating pull chain. Body side wall 12 is provided with spaced openings 15, 16 for reception of electric wires, as best shown in Fig. 2, and similarly oriented with respect to each other and in open communication with aforementioned openings 15, 16, are slots or chambers 17, 18 which, as hereinafter more fully described, are adapted to frictionally receive and retain contact members 30, 30 in the assembled condition of the switch.

Chambers 17, 18 are in open communication through openings 19, 20 with annular rotor-receiving chamber 21 which is located medially of body or case 10. It will be noted that the above described arrangement positions pull chain receiving chamber 14 and each contact member receiving chamber 17, 18 in radially or circumferentially spaced relation to annular rotor-receiving chamber 21.

In preferred form, body or case 10 is provided with one integral end wall 22. On the inner surface of wall 22 and medially of chamber 21 is formed a hollow cylindrical boss or bearing 23 one side wall of which is provided with a recess 24 to receive the outwardly bent end 41 of torsion spring 40 and to form a base for said spring end. As above mentioned, boss or bearing 23 is medially hollowed out to frictionally receive one end of a parts-supporting cylindrical axle 25.

The walls separating contact member receiving chambers 17, 18 from rotor-receiving chamber 21 extend to the full height of side wall 12, but the arcuate wall separating pull chain receiving chamber 14 from rotor-receiving chamber 21 is in part cut down or recessed as at 26 to accommodate and guide the outwardly extending arm 71 of rotor-actuating member 70.

In an area generally opposite planar area 11 an opening 29 is provided to receive the threaded end 96 of cover-retaining self-threading screw 95.

Identical contact members 30, 30, best shown in Figs. 2 and 3, each comprise a unitary flat spring-like conducting metal structure which along one end is bent backward toward itself into a U indicated by reference numeral 32 to receive within the U the solder-attached ends of current-carrying wires. The distances between the legs of the U of the contact members are such that, when both such members are inserted into chambers 17, 18 they will frictionally engage adjacent walls, their ends 31, 31 abuttingly engag-

ing abutments 27, 28. Beyond the U each contact member is bent backwardly a slight amount as at 33 then forwardly in an arc as at 34 the curve of which coincides generally with the shape of the hereinafter described peripheral teeth 61 of rotor 60.

Contact spider 50 is a unitary metal current carrying structure preferably formed of copper or copper alloy. It comprises a generally rectangular planar base portion 51 provided with an annular central opening 52 the cross dimension of which is such as to permit the spider to be externally borne on boss 23 in the assembled condition of the switch. Contact springs 53 are bent to generally right angled relation to base portion 51 and are arcuately curved to conform generally to those alternate teeth 61 of rotor 60 which they engage and by which they are carried.

Rotor 60 is a unitary structure of non-conductive material. It is provided with an even number of peripheral ratchet teeth 61 (in this instance shown as eight) which have arcuate exterior surfaces interspersed between which are abrupt re-entrant indentations, one of which is indicated by reference numeral 62. The free outer ends 34, 34 of contacts 30, 30 contact the arcuate exterior surfaces of spaced teeth 61, 61 in the broken-circuit condition of the switch or the exterior arcuate surfaces of laterally adjacent contact prongs 53, 53 in the closed-circuit condition of the switch. Rotor 60 has a cylindrical periphery 63 and at its end opposite teeth 61 is provided with a ratchet surface comprising a number of arcuate ratchet teeth 64 having abrupt faces 65. There are as many ratchet teeth 64 as there are other ratchet teeth 61 and all the ratchet teeth are similarly oriented to permit only uni-directional rotation of rotor 61 on boss 23, said rotor being centrally bored to provide an opening 66 into which said boss may axially extend.

A rotor actuating member 70 is provided with spaced arcuate arms 72, 72 which are inwardly inclined from the normal plane of the body of the structure so that the free ends 73, 73 thereof contact abrupt ratchet faces 65 and may impart uni-directional rotation to rotor 60. Rotor actuating member 70 has a central opening 74 to receive and partially rotate upon axle 25. Member 70 is in part slotted as at 75 and recessed as at 76 to receive the end 42 of torsion spring 40, the opposite end 41 of which is fixedly retained in hereinabove described slot 24. As previously mentioned, in the assembled switch, actuating member arm 71 extends into pull chain receiving chamber 14 through the wall recess indicated by reference numeral 26 and the pull chain 77 is attached to the end of arm 71 by a pivotal connector 78. When rotor actuating member 70 is about to be swung through the arc comprising its full operating movement on axle 25 the free ends 73, 73 of arms 72, 72 contact a pair of opposed abrupt ratchet faces 65, 65 moving ratchet 60 a distance equivalent to the peripheral dimension of a single ratchet tooth 61. When pull cord or chain 77 is released, actuating member 70 automatically returns to its starting position under the urging of torsion spring 40, the free ends 73, 73 of arcuate arms 72, 72 sliding along the inclined surfaces 67 of end ratchet teeth 64 until engaged with newly brought forward abrupt faces 65, 65 and in readiness for a new contact making or breaking action.

While but one spacer or washer 80 is shown in Fig. 1, it will be seen from reference to Figs.

5 and 6 that, if desired, at least two thereof may be used to provide free space between the case or body 10, the cover 90 and the actual switch mechanism. It will also be seen that the free end axle 25 terminates coplanar with the upper or end surfaces of the body walls, cover 90 in its attached and body-covering position serving to hold the axle firmly in desired position.

When all the parts shown in Fig. 1 have been assembled within body or case 10 in the manner above described and as shown in Figs. 2 through 6, the cover 90 may be attached. This is done by aligning cover opening 91 with body opening 29 and drawing the parts together by inserting screw 95 between them. Opening 29 is unthreaded at the time of insertion of the above mentioned screw which, during insertion, cuts out its own retaining threads. With screw 95 inserted, cover 90 is rotated into full body covering position at which time cover annular periphery 93 will register with body portion exterior wall 12 and cover linear portion 94 will register with planar body area 11. Pull chain 77 may then be inserted through the interior opening 102 of clip cylindrical portion 101, and clip 100 may then be attached in the manner hereinafter described.

Clip 100 comprises a planar portion 103 of generally rectangular shape bent upwardly along opposite lateral sides of which are a relatively narrow side portion 104 having spaced indent lugs 105 thereon and a side portion 107, wider than portion 104, which has spaced indent lugs 108 thereon. As best shown in Fig. 1, cover 90 is provided with a pair of aligned spaced openings 92, 92 adjacent edge portion 94, and, as shown in Fig. 6 body portion 10 has similar openings 109 formed therein. Clip 100 is most readily attached by positioning lugs 108 within openings 109 and biasing side portion 104 over the edge of cover 90 until lugs 105 may be snapped into openings 92, 92.

We claim:

1. In an electric switch, a unitary case having integral interior walls which divide the body into a plurality of switch parts-receiving chambers, the parts contained within said chambers being insulated from contact or arcing relation by said walls, said chambers including a centrally disposed rotor-receiving chamber, at least two electric contact member-receiving chambers and a pull chain-receiving chamber, said contact member-receiving chambers being in adjacent relation to one another and in generally circumferential relation to said rotor-receiving chamber and the wall separating each contact member-receiving chamber from said rotor-receiving chamber having an opening therein communicating with the latter through which the free ends of electric contact members may extend in rotor-engaging relation, said pull chain-receiving chamber being of generally arcuate configuration and arranged exteriorly of said rotor-receiving chamber and circumferentially spaced from said contact-receiving chambers, the wall separating said rotor-receiving and said pull chain-receiving chamber being in part of less height than the other walls to permit extension therethrough of a relatively thin rotor-actuating member one end of which is engaged by a pull chain contained within and guided by the wall of said pull chain-receiving chamber, one end of the latter being in open communication with the exterior of said case so the pull chain may be used to actuate the switch parts.

2. In an electric switch the combination comprising a molded unitary body having an integral end wall, integral side walls and integral interior walls, said walls defining in said body a medial chamber, a pair of contact member-receiving chambers and a flexible element-receiving chamber, an axle mounted on said end wall and extending upwardly centrally of said medial chamber, a contact-making rotor means borne by said axle, a pair of contact members each bent backwardly upon itself at one end, said pair of contact member-receiving chambers frictionally retaining the backwardly bent portions of said contact members and being in spaced but adjacent relation to one another and in generally circumferential relation to said medial chamber, the wall separating each of said pair of chambers from said medial chamber having a recess therein through which the free ends of said arms extend into said medial chamber in rotor means-contacting relation, a rotor-actuating member mounted for spring loaded reciprocal movement on said axle, said member having a thin operating arm, a flexible element positioned for back and forth movement in said flexible element-receiving chamber and engaged with the free end of the operating arm of said rotor-actuating member, said flexible element-receiving chamber being of generally arcuate configuration.

ration to guide said flexible element and being arranged circumferentially of said medial chamber and generally opposite to said contact member-receiving chambers, the wall separating said last-named chamber from said medial chamber being recessed sufficiently along its top to permit reciprocal movement thereabove of the arm of said rotor-actuating member, a generally planar parts-retaining cover for said body, and means for holding said cover on said body.
